CLAIM

We claim the ornamental design for a lamp control module, as shown and described.

DESCRIPTION

FIG. 1 is a top perspective view of a lamp control module according to a first embodiment of our new design.

FIG. 2 is a bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is a bottom perspective view of a lamp control module according to a second embodiment of our new design.

FIG. 10 is a front view thereof; and,

FIG. 11 is a bottom view thereof, the top perspective, rear, left side, right side, and top views, respectively, of the second embodiment being identical to the top perspective, rear, left side, right side, and top views of the first embodiment.
